UNITED STATES PATENT OFFICE.

HARRY A. ATWATER, OF KANSAS CITY, MISSOURI.

GAS-BURNING HEATER.

Application filed February 18, 1924. Serial No. 693,545.

The present invention relates to heating apparatus, with particular relation to heating appliances using gaseous fuel, and aims to provide a novel construction for enabling 5 a new and efficient method to be employed for feeding the gas and air into the fire chamber, for the purpose of preheating the air and so controlling the mixture of the gaseous fuel with the preheated air as to effect 10 certain chemical changes of a nature adapted to produce a more efficient transmission of heat by means of radiation.

Accordingly, the present invention resides 15 in an improved combustion method, as well as suitable provision for carrying out the same in practice, the principal features of the same consisting in the preheating of the air whereby the combustion is supported, and feeding the gas into the combustion chamber 20 without being previously mixed with air, and so regulating the flow of gas and preheated air as to break down the gaseous fuel into component products having greater heat radiating properties, the combustion of 25 which will thereafter produce the principal heating action developed by the furnace or heater and with a far greater intensive effect than that produced by the burning of the original gaseous fuel by ordinary 30 methods.

With this general object in view, the invention will now be described by reference to the accompanying drawings illustrating one form of construction which I have devised for embodying the proposed improvement and practicing the new method, after which those features deemed to be novel will be particularly set forth and claimed.

In the drawings—

Figure 1 is a central vertical sectional view illustrating a portion of a hot air furnace supplied with a heater construction embodying the present invention;

Figure 2 is a transverse section, taken on the line II of Figure 1;

Figures 3 and 4 are top and bottom perspective views, respectively, illustrating the air preheating device, forming a part of the invention;

Figure 5 is a perspective view illustrating a block member used for housing the nozzle employed for feeding the gaseous fuel into the combustion chamber; and

Figure 6 is a perspective looking at the front end of the preheater member.

In those types of heaters, where the fire

box or combustion chamber is entirely surrounded by heat-absorbing surfaces, the most efficient method of transmitting the heat of combustion is, obviously, by means of radiation, as the conditions are not of a character favorable for effective transmission of heat by either conduction or convection. The usual type of gas burner utilizes the familiar principle of the Bunsen burner with its short, pale blue, transparent and non-luminous flame. This character of flame is a very poor radiator, having a small flame body, and being best adapted for transmitting heat over a small area at the point of contact with the tip of the flame. The radiating power of a flame depends upon its temperature and the density of the gas, and the presence in the flame of solid particles such as carbon. In the Bunsen type of burner, the flame is cooled at the outset by an admixture of air in the gas tube. Moreover, the mixture of the air with the gas is so intimate that it burns readily and very rapidly.

The present invention takes advantage of the fact that, while gases in general possess poor heat radiating properties, illuminating and natural gases may be caused to burn with a flame body that is opaque or non-transparent and impregnated to a certain extent with carbon, so as to produce a flame having high heat-radiating properties. While the chemistry of combustion of hydrocarbons is not at all thoroughly understood, the properties of the constituent gases present in the usual commercial product, and the commonest reactions taking place on preheating and in the usual process of combustion, are sufficiently familiar and the results well enough understood for the purposes of the present invention. Some of these hydrocarbons, such as methane and ethane, burn with non-luminous flames and are comparatively poor radiators of heat. Other hydrocarbons, particularly acetylene and benzene, burn with highly luminous flames, having comparatively very high radiating properties. It is also found that methane and ethylene, which are present in substantial amounts in all the commercial forms of illuminating and natural gases, when exposed to the action of sufficient heat, are readily converted into acetylene and hydrogen; and also, that methane, which is the predominant constituent of most commercial gases, and, in turn acetylene, tend

to polymerize when heated to a given temperature, and one of the primary products of this polymerizing action is benzene, a hydrocarbon of much greater density and one having even higher radiating properties than acetylene. Now, if the temperature is still further increased, some of these constituent gases will become dissociated; for example, acetylene, being an endothermic compound, will readily dissociate into carbon and hydrogen, and this free carbon obviously will still further increase the luminosity and the heat radiating power of the flame. Since the ignition temperature of methane, the predominating hydrocarbon constituent of the usual commercial gas, is below its polymerizing and dissociating temperatures, it is apparent that when such gas is burned rapidly with a complete air mixture as in the ordinary gas burner, these various hydrocarbon constituents such as methane, ethylene, etc., will simply burn as methane, ethylene, etc., respectively, with no incidental reactions of the type above referred to. The resulting flame, therefore, is simply one having a body of relatively short expanse, and containing no solid particles or luminous or dense gases to impart the desired high radiating properties to the flame. This may be termed the most inefficient manner of burning gaseous fuel, so far as securing the maximum radiating power of the flame is concerned.

For securing a more efficient combustion of the gaseous type of fuel, as regards increased radiating properties, I have devised a heater construction such as illustrated in the accompanying drawings. In these drawings I illustrate the apparatus as embodied in a furnace of the hot air type, in which the usual coal grates are removed from the fire pot or combustion chamber 10 and after also removing the ash pit door, I also insert within the ash pit 11 an air preheater device, in the position illustrated in Figures 1 and 2. Referring to Figures 3, 4 and 6, this preheater device comprises metallic casing 12, having side flanges 14 and also an end flange 15 at what may be termed the inner end of the casing, in addition to which the interior of the casing is also provided with a set of vertical partition members 16 terminating short of the end flange 15. These flanges and the two outer partition members 16 are designed to rest upon the floor 17 of the ash pit 11, as clearly illustrated in Figure 2. At the ash pit door, the preheater is provided with a face plate 19 formed with an opening 20 for the mounting of the fuel burner nozzle 21, which may be of any desired type for the burning of gaseous fuel, so long as the same operates to feed the gas to the combustion chamber 10 without any admixture of air with the fuel prior to its discharge into said chamber.

The face plate 19 also provides air inlet openings 22 for admitting air into the outer air preheating passages 23. At the rear end of the preheater, obviously, as illustrated in Figure 4 air passages 23 communicate with the inner air preheating passages 24, the forward ends of which communicate with an air discharge opening 25 formed in the top of the front end of the casing 12, directly beneath fuel burner nozzle 21.

Preferably, a refractory arch tile block 30, of the form best illustrated in Figure 5, is mounted upon the front end of the preheater member, for enclosing the nozzle member 21, this block being provided with an opening or recess 31 for registry with the opening 25 through which the preheated air is admitted to the burner space. A flaring space is provided for the discharge of the gas and preheated air from the arch block 30, by means of the diverging side walls 32 of the housing space within said block. The upper face of the preheater member 12 is also preferably formed with suitable ribs 34 in front of and at the sides of the air inlet opening 25, for fitting correspondingly located recesses 35 in the bottom face of the block 30, thereby insuring the proper positioning of this block and the retaining of the same in its proper relation to the nozzle 21.

The remainder of the top face of the preheater member 12 is also preferably covered with suitable refractory material, such as split tiling, which is designed to be just thick enough to protect the metallic substance of a preheater from any damage due to the heat of the combustion chamber, and yet not so thick as to prevent an efficient flow of heat therethrough to the air preheating passages 23 and 24. A further function of this refractory floor thus provided by this tiling 36 is that of reflecting some of the heat from its surface back into the body of the flame in the chamber 10.

It is also proposed to set blocks 37 of tiling on end around the sides and rear of the refractory flooring formed by the tiling 36, with the upper ends of the blocks 37 arranged in the space left by the removal of the grates, as clearly illustrated in Figures 1 and 2. It is also preferred to form a bed of sand 38 around the preheater member, or between it and the sides of the ash pit 11, which acts as a further insulation against loss of heat, and also serves to brace and support the preheater member in the position illustrated.

In the operation of the heater, gas will be admitted through the nozzle 21, this gas being discharged from the nozzle in a pure or undiluted condition, no air having been mixed with the gas prior to its admission into the combustion chamber. All of the air preheating passages, including the openings

22 and the opening 25 into the burner chamber, are so proportioned as to admit the proper amount of air. In its passage through the preheating passages 23 and 24, 5 this air undergoes a marked increase in temperature, on account of the highly heated condition of the floor of the combustion chamber, and, on entering the burner chamber, surrounds the gas issuing from the 10 nozzle 21. Ignition of the gas takes place at the tip of the burner, but combustion proceeds only on the outside of the body of the gas where the gas comes in contact with the air. As this body of gas, surrounded by a film or coating of flame, 15 travels over the refractory floor and through the combustion chamber, the heat imparted to the gas body from the preheated air and by reflection from the floor of the combustion chamber, causes the various chemical 20 reactions above referred to, to take place; that is to say, by causing the flow of gas to take place in a steadily moving stream of comparatively low velocity as well as of 25 rather substantial depth or cross-section, any eddying or turbulent action is prevented and combustion is carried out relatively slowly as compared with the usual high velocity feeding action which breaks up the gas with 30 a view to intimately mixing it with air as rapidly as possible. Hence, in my process, the combustion is initiated on the exterior of the gas stream, and the heat produced by this combustion of the gas on the exterior 35 of the gas stream as well as the heat reflected and radiated from the floor of the chamber effects the breaking down of the main body of the gas on the interior of the gas stream into various polymeric components having much greater heat radiating 40 properties, as well as to dissociate some of these constituent gases, and releasing free carbon. The combustion of these reaction products brings about combustion conditions 45 affording vastly greater radiating powers than can be secured by the immediate combustion of the constituents of the original fuel if burned at once without any intermediate reaction. By proper design and 50 regulation, these reactions may be so controlled as to produce and maintain a full long flame body within the combustion chamber, in which these polymeric hydrocarbons, of intense radiant activity, are 55 burning, as well as to secure the presence of an abundance of free carbon, thereby adding further to the heat radiating activity of the flame. The result is the complete and 60 most efficient utilization of the heating surface of the fire pot which is exposed to this radiated heat, as well as a maintenance of the most efficient condition under which fuel of this character may be burned.

It will therefore be apparent that I have

devised a practical and efficient method and 65 apparatus for carrying out the proposed objects of the invention, and while I have illustrated what now appears to constitute the preferred form of embodiment, as well as method of practicing the invention, I desire 70 to reserve the right to make all such changes or modifications as may fairly fall within the scope of the appended claims.

What I claim is:

1. The process of producing combustion 75 of hydrocarbon gas in a heater which consists in conducting heated air into the combustion chamber of the heater, feeding the pure gas, unmixed with air and in a steady unturbulent stream of comparatively low 80 velocity and substantial cross-section, into the heated air zone within said chamber, and thereby igniting and burning the gas at the exterior of said stream and by the heat thus generated breaking down the gas 85 at the interior of the stream into its components and producing the principal heating action by the combustion of said components.

2. The process of producing combustion 90 of hydrocarbon gas in a heater which consists in conducting heated air into the combustion chamber of the heater, feeding the pure gas, unmixed with air, in a steady unturbulent stream of comparatively low velocity and of substantial depth and in sheet 95 form spreading out over the floor of the chamber, and thereby igniting and burning the gas at the exterior of the stream and by the heat thus generated and also reflected from said floor breaking down the gas at 100 the interior of the stream into its components and producing the principal heating action by the combustion of said components.

3. The process of producing combustion 105 of a hydrocarbon gas within a heater which consists in heating air for supporting the combustion by conducting it past exterior surfaces of the heater maintained hot by heat transmitted from the combustion chamber of the heater, conducting said air into the combustion chamber of the heater, feeding the pure hydrocarbon gas, unmixed with air, in a steady unturbulent stream of comparatively low velocity and of substantial 110 depth and in sheet form spreading out over the interior surfaces of said chamber, and thereby igniting and burning said gas first at the exterior of the gas stream and by the heat thus generated and also reflected and radiated from said interior surfaces of the chamber breaking down the gas at the interior of the stream into its components and producing the principal heating action by 115 the combustion of said components.

In witness whereof I hereunto affix my signature.

HARRY A. ATWATER.
